BURNER FOR LIQUID FUEL

Victor Ipold, Vienna, Austria, assignor to Technik
& Investment A.-G., Vaduz, Liechtenstein

Application January 31, 1933, Serial No. 654,515
In Austria May 12, 1930

5 Claims. (Cl. 158—69)

The invention relates to a vaporizing burner for heating appliances utilizing petroleum or the like. The burner comprises a vaporizer, a fuel valve for regulating the admission of fuel to the vaporizer, and a gas nozzle which is connected to the vaporizer and ejects the vaporized fuel or gas with which it is supplied from the vaporizer. A mixing tube may be provided for the reception of the gas from the gas nozzle.

10 The gas nozzle is equipped with a valve which may be the usual needle, for regulating its free sectional area, and mechanism is provided for operating the needle.

15 The fuel valve is operated by the usual means, such as a knurled hand wheel on its spindle.

It has been found that the sequence in which the needle and the fuel valve are operated is important. Gas residues form on the needle in the shape of coke which is very hard when cold

20 and, if the needle is operated before the vaporizer has been heated, its movement may be obstructed to such an extent by the hard coke that the needle is bent or otherwise damaged, and the gas nozzle does not function properly.

25 Therefore, the needle must only be operated after the gas nozzle has become hot and the coke, if any, on the needle has been softened. The heating of the gas nozzle is accelerated by placing the upper end of the gas nozzle substantially 30 at the level of the vaporizer.

The needle-operating mechanism is driven by the means for operating the fuel valve but the connection for driving the mechanism from the means is so designed that the mechanism is engaged only after the means has performed a part 35 of its movement for opening the fuel valve.

By these means, the fuel valve is opened first and the fuel is evaporated in the evaporator and heats the nozzle until its needle can be operated 40 safely, and only after this condition has been established, the mechanism is engaged and the needle operated.

45 Preferably, means are provided for preventing inadvertent operation of the mechanism for the needle so that the burner becomes foolproof. Such means may be a member for locking the mechanism against operation while the means for operating the fuel valve performs its partial movement, and for releasing the mechanism after such partial movement has been completed. If such a locking member is not provided it may occur that an unskilled operator handles the mechanism before the fuel valve is opened, and bends or damages the needle of the gas nozzle.

50 A suitable means for connecting the means

for operating the fuel valve, and the mechanism for operating the needle, is a stop control of well-known type. Such a control not only effects the subsequent operations of the means for operating the fuel valve, and the mechanism for operating the needle, and the locking and releasing of the mechanism, but it also re-acts on the fuel-valve operating means by limiting the movement of the fuel valve in the direction away from its seat so that the fuel valve is not screwed out too far and its stuffing box damaged.

5 In the old burners of this type, the fuel valve and the needle of the gas nozzle can be operated quite independently of each other. In other burners, also of this type, the fuel valve and the needle are operated together by positive means but such means are not designed for first operating the fuel valve and subsequently operating the needle.

The burner is of the kind in which a mixing 20 nozzle disposed above a vertical gas nozzle is located beneath a mixing cap provided with lateral effective heating flame apertures which cap seats on a vaporizer in the form of a hollow annulus conductively connected with the gas nozzle 25 leaving apertures for jet flames for heating the vaporizer.

Hitherto in such burners the mixing nozzle, consisting of a cylindrical tube, as well as the vaporizer annulus were arranged comparatively 30 far above the gas nozzles and the latter were connected to the annulus by correspondingly long upwardly extending U-tubes so that the desired small constructional height of the burner was not obtained nor was there a small path for 35 the gas nor any adequate heating of the gas nozzle so that the latter became foul too rapidly in consequence of gas residues.

According to the invention these disadvantages are wholly avoided in that the vaporizer ring is 40 attached as a marginal rim to a short mixing nozzle which is broadened at the bottom in a cup-like manner and in that the vaporizer annulus is connected with the gas nozzle, which for instance may be arranged in the plane of 45 the annulus, by spoke members one at least of which is hollow.

By the aforesaid operative connection of the means for operating the fuel valve on the one hand, and the nozzle valve on the other hand, the operation of the burner is simplified and facilitated so that it may be operated without risk by any unskilled person.

55 In the accompanying drawings, a burner em-

bodying my invention is illustrated by way of example.

In the drawing

Fig. 1 is a vertical section,

5 Fig. 2 is a plan view of the burner, with removed hot plate,

Fig. 3 is a section on the line 3—3 in Fig. 2, drawn to a larger scale,

10 Figs. 4 and 5 are sections on the corresponding lines in Fig. 2, and

15 Fig. 6 is an end elevation of the control mechanism, viewed from the right in Fig. 5, with the side wall of the burner frame at the right, and the handle for turning the spindle of the fuel valve, removed.

20 Referring now to the drawings, 14 are four feet on which the frame 1 of the burner is mounted. 2 is a hot plate, with a hole 15, which may be detachably placed on, or hinged to, the frame 1. 25 3 is staying or bracing plate in the frame which is readily accessible for cleaning and inspection after the hot plate 2 has been removed or turned up on its hinge, not shown. The plate 3 has a hole 4 with a downwardly directed rim for the reception of a cup 10 on the vaporizer 9. The cup 10 and the rim of the hole 4 make up an annular slot 29.

30 5 is a fuel tank for petroleum or other suitable liquid, and 6 is the usual manually operated air pump for placing the fuel in the tank under pressure. 7 is a fuel-supply pipe for the burner. The pipe 7 is connected to the tank 5 at one end and at its other end has a valve casing 11. The fuel valve 16 is formed on the inner end of a spindle 18 and fits a seat where the pipe 7 is connected to the casing 11. 19 is a thread on the spindle which fits in a female thread of the casing 11, 20 35 is a cap nut for packing the spindle in the casing 11, and 17 is a knurled hand wheel on the outer end of the spindle.

40 9 is the vaporizer already referred to. It is an annular tube whose bottom is connected to the valve casing 11 by a hole 8, so that the supply of fuel to the vaporizer 9 from pipe 7 is controlled by the valve 16.

45 25 is a mixing tube which is mounted within the circular area defined by the annular vaporizer 9. The mixing tube is comparatively short and cylindrical, with its lower end flared 50 to the inside diameter of the vaporizer 9. Mounted above the upper end of mixing tube 25 is an inverted mixing cap 26, with a radially slotted skirt 27 whose lower end 28 is seated on the vaporizer 9 and recessed as shown so as to define 55 flame passages with the upper face of the vaporizer 9. The mixing cap may be pressed from any suitable material, such as talcum-magnesite.

60 Mounted below the mixing tube 25 and co-axially with respect to the burner, is a vertical tube 22. Inserted in the upper end of the tube is the 65 gas nozzle 21, with a bore, Fig. 4. The tube 22 is connected to the vaporizer 9 by a tubular stay 12 and a solid stay 13. The tubular and the solid stay also serve as heat conductors to the nozzle 21.

70 33 is a needle valve which projects into the bore 37 of the gas nozzle 21, 34 is a slide which is mounted to reciprocate in the nozzle tube 22, with the needle valve 33 at the upper end of the slide, 36 is a pin on a crank disk 35 which pin engages in a slot of the slide 34, and 23 is a spindle in a packed bearing 24 of the tube 22. The disk 35 is secured on the inner end of the spindle. Raising and lowering of the valve 33 is effected by turning the spindle 23 and the free sec-

tional area of the bore 37 in the nozzle 21 is regulated thereby.

5 As mentioned, it is not desirable that the fuel valve 16 and the needle valve 33 should be operated independently. A connection is therefore provided for the spindles 18 and 23 which will now be described with reference to Figs. 5 and 6. 38 is a control mechanism on the spindle 23 of the needle valve 33, 39 is a disk on the spindle 18, with a block 41 and a pin 40 for cooperation with the control mechanism 38, 42 is a recess in the block 41, and 43, 44 are slots in the stop 38 which are adapted to be entered by the pin 40. Fig. 6 shows the parts of the control mechanism in the position in which the spindle 23 of the 15 gas nozzle 21 is locked against operation, as the member which is between the slots 43 and 44, is held against rotation by the solid or non-recessed cylindrical portion of block 41. When the spindle 18 is turned anti-clockwise by the knurled 20 hand wheel 17, the pin 40 on the disk 39, and the recess 42 in the block 41, both move toward the slot 43. When the pin 40 engages the slot 43 (or in another position the slot 44) the locking is released as the arms adjoining the slot 43 (or 25 44) enter the recess 42. The spindle 23 is then operated by the pin 40. In this manner, the fuel valve 16 is operated independently of the spindle 23 and the gas nozzle 21 for a part of its movement and opened as wide as required for heating the vaporizer 9 and, through it, the gas nozzle 21. On the other hand, the spindle 23 cannot be operated independently of the spindle 18 as it is locked by the control 38. The coke or the like on the needle 33 is softened by the heat before the needle can be moved, and the positive locking of the spindle 23 renders the apparatus entirely foolproof. The operator has to turn only the knurled hand wheel 17 for operating the fuel valve as well as the gas nozzle, and therefore the 30 operation of the burner is as simple as that of the burners referred to above in which the fuel valve and the needle are operated together, while its function is far superior to that of these burners, for the reasons stated.

35 45 For starting the burner, a cup 30 is secured to the lower end of the nozzle tube 22. Fuel, such as spirits or the like, is supplied to the starting cup 30 through an open channel 31 with an igniting conductor 32. The conductor which is 50 placed on the bottom of the channel, consists of a non-combustible and porous material, for instance, asbestos.

55 As mentioned, the cup 10 on the vaporizer 9, which, by the way, is preferably made of brass sheet-metal, like the mixing tube 25, defines a circular slot 29 with the flanged hole 4 in the plate 3. The flame from the starting cup 30 and air for combustion have free access through the slot 29.

60 In operation, the fuel in the starting cup 30 is ignited and, after the burner has been heated thereby, the fuel valve 16 is opened by turning the hand wheel 17 on the spindle 18 anti-clockwise. Fuel is now admitted to the vaporizer 9 through 65 the hole 8, Fig. 3, and ignited after having been vaporized. The flame now has its full intensity. If it is desired to have a less intense action of the flame, the hand wheel 17 is turned further anti-clockwise until the pin 40 on the disk 39 70 engages in the slot 43 of the control mechanism 38 and rotates the stop, causing the spindle 23, through the medium of the needle valve 33, to restrict the free sectional area of the nozzle 21. The control mechanism permits rotation of the 75

spindle only through 180 degs. and the rotation of the spindle 18 of the fuel valve is restricted correspondingly, so that the spindle cannot be screwed out so far as to damage the packing in 5 the cap nut 20, by its thread 19.

The upper end of the gas nozzle 21 is substantially at the level of vaporizer 9 so that the nozzle is heated rapidly and efficiently after the fuel valve 16 has been opened. The mixing tube 25 10 is of cup-like shape at the bottom, and the vaporizer 9 is connected to this cup as a marginal rim.

I claim:

1. In a burner for liquid fuel, a vaporizer, a fuel valve for regulating the admission of fuel to the vaporizer, means for operating the fuel-regulating valve, a gas nozzle for ejecting the fuel which has been vaporized in the vaporizer, a conduit for conducting fuel vapor from the 20 vaporizer to the nozzle, a valve for regulating the free sectional area of the nozzle, and mechanism operatively connected to said fuel-valve operating means for operating said nozzle-regulating valve and for limiting the movement of said 25 means when the fuel valve is moved in a direction away from its seat.

2. In a burner for liquid fuel, a vaporizer, a fuel valve for regulating the admission of fuel to the vaporizer, means for operating the fuel-regulating valve, a tube, a conduit for conducting fuel vapor from the vaporizer to the tube, a nozzle in said tube for discharging vapor therefrom, a valve for regulating the free sectional area of the nozzle, eccentric means for operating said 35 nozzle valve, a spindle for operating said eccentric means which is operatively connected to said fuel-valve operating means, and a control mechanism comprising a pin and slot mechanism for actuating said nozzle-regulating valve in dependency of the fuel valve operating means.

3. In a burner for liquid fuel, a vaporizer, a fuel valve for regulating the admission of fuel to the vaporizer, means for operating the fuel regulating valve, a gas nozzle for ejecting the fuel 40

which has been vaporized in the vaporizer, which nozzle is arranged with its upper end substantially at the level of said vaporizer, a conduit for conducting fuel vapor from the vaporizer to the gas nozzle, a valve for regulating the free sectional area of the nozzle, and mechanism operatively connected to said fuel valve operating means for operating said nozzle regulating valve and for limiting the movement of said means when the fuel valve is moved in a direction away 10 from its seat.

4. In a burner for liquid fuel, a mixing tube having a cup-like shape at the bottom thereof, an annular vaporizer connected to the mixing tube as a marginal rim, a fuel valve for regulating the admission of fuel to the vaporizer, means for operating the fuel regulating valve, a gas nozzle for ejecting the fuel which has been vaporized in the vaporizer, a conduit for conducting fuel vapor from the vaporizer to the gas 20 nozzle, a valve for regulating the free sectional area of the nozzle, and mechanism operatively connected to said fuel valve operating means for operating said nozzle regulating valve and for limiting the movement of said means when the 25 fuel valve is moved in a direction away from its seat.

5. In a burner for liquid fuel, a vaporizer, a fuel valve for regulating the admission of fuel to the vaporizer, means for operating the fuel 30 regulating valve, a gas nozzle for ejecting the fuel which has been vaporized in the vaporizer, a conduit for conducting fuel vapor from the vaporizer to the nozzle, a valve for regulating the free sectional area of the nozzle, eccentric means for operating said nozzle valve, a spindle for operating said eccentric means which is operatively connected to said fuel valve operating means, and a control mechanism comprising a pin and 35 slot mechanism for actuating said nozzle-regulating valve in dependency of the fuel valve operating means.

VICTOR IPOLD.
